UNITED STATES PATENT OFFICE.

WILHELM JULIUS TEUFEL, OF STUTTGART, GERMANY.

BODY-BELT.

SPECIFICATION forming part of Letters Patent No. 733,092, dated July 7, 1903.

Application filed April 26, 1902. Serial No. 104,858. (No model.)

To all whom it may concern:

Be it known that I, WILHELM JULIUS TEUFEL, a citizen of the German Empire, residing at Stuttgart, in the Kingdom of Würtemberg, Germany, have invented certain new and useful Improvements in or Connected with Body-Belts, Corsets, and the Like, of which the following is a description, reference being had to the accompanying drawing, and to the letters of reference marked thereon.

The object of this invention is to obtain a variable elastic body-belt, and for this object the belt is provided with a peculiar stomach-piece or stomacher, which always exactly follows the form of the body without forming creases even where there is a great alteration of form. This action of the stomach-piece is obtained by its peculiar shape, combined, if desired, with the use of a material which in itself is known already, but is here employed in a peculiar manner. This improved stomach-piece is provided on both sides with slits or notches, and on the flaps remaining between these notches bands or strips are fastened, by means of which the stomacher may be suitably tightened in any position or height, while always fitting without any formation of creases flat on the abdomen, no matter what form the latter may have, in consequence of the notches cut in the ends of the stomacher. By the use of so-called "rectangular material" for the stomacher in which the threads lie transversely to the direction of the binder the action of the stomacher is strengthened, such fabrics being much more resistant than stockinet, for instance, and yet having sufficient elasticity in consequence of the transverse position of the threads which do not shrink crookedly.

The abdomen has, as is well known, a varying more or less arched spherical form, and when the stomach part of the binder or belt is intended to always exactly fit itself to suit this altering form it is necessary that the side parts of the stomacher should be able to contract and expand. In the body-belts hitherto employed this is not the case. It is true that in some body-belts an adjustment of the stomacher above and below may take place, but no contraction or extension of the sides is possible, and therefore when the belt is considerably taken in or let out folds are formed at the sides of the stomacher even when the latter was originally carefully fitted to a given shape of the abdomen. If the sides or ends of the stomacher are specially stiffened, these stiffeners bend and only partially rest on the abdomen, whereby a one-sided pressure on the wall of the abdomen is produced. If, further, stockinet be employed for the stomacher in body-belts which are more particularly intended for use in the case of corpulency or the like the following drawbacks arise: The stockinet material, which is elastic in all directions, expands and the stomach part of it contracts over the central part of the abdomen which has the greatest curvature and where the belt has always to withstand a greater pressure than above or below, and the upper and under part of the stomacher each being provided with fastening-bands cannot expand. In wearing the belt, therefore, there is formed in the center of the stockinet stomacher an enlargement which remains curved in a spherical form, which causes it in the case of alteration in shape of the abdomen to only support the latter by its edges. As, however, by the wearing of such body-belts according to their object the abdomen is reduced in size and curvature, an adjustment more particularly of the stomacher is necessary; but in consequence of the adjusting devices hitherto employed it can only be adjusted uniformly circularly until the upper and under bands of the stomacher, which bands are rendered inelastic by the fastening-strips, lie flat on the abdomen. The expanded center part of the belt, however, does not fit closely to the abdomen. The adjustability therefore ceases for this part, for which it should be particularly employed, and the part of the abdomen which requires support is the one which is deprived of support and elastic resistance, which the further formation of the abdomen requires. Such body-belts fulfil their object to a very limited extent. The attempt to remove this drawback by drawing the stomach part or stomacher upward or downward by means of shoulder-bands or thigh-straps can only diminish to a small extent the drawback, and produces in turn the great drawback that the wearing of thigh-straps and shoulder-bands is found very annoying and inconvenient and rapidly causes

chafing. All these drawbacks are removed by the stomacher of this improved body-belt, which is shown in one form of construction in the accompanying drawing.

5 The stomach part *a* has flaps *b* formed thereon by notches or slits being cut at each side, to which flaps the fastening bands, straps, or the like *c* for adjusting the belt are attached. The upper and under and, what is 10 the essential feature, the central part of the belt may thus as shown be drawn tighter or let out independently of one another in a sufficient and suitable manner without the formation of folds or creases. In consequence 15 of the great power of fitting and its considerable adjustability the thigh-straps and shoulder-supports unavoidable in such belts require to be drawn much less tightly, which renders the wearing of such straps considerably 20 less unpleasant. If, further, the stomacher be formed of rectangular fabric, which is cut transversely from the material—that is to say, the threads lying transversely to the direction of the belt—it is elastic in all directions—that is to say, upward or downward. 25 Its power of stretching is, however, more limited, but still quite sufficient. On the other

hand, its durability is greatly increased, and also the result is obtained that on the pull on the stomacher being released it returns to its 30 original form, which again considerably increases the utility of the body-belt.

The back part of the body-belt, as well as the means for connecting the stomacher and the back part, may be arranged in any known 35 manner.

Having now particularly described and ascertained the nature of my said invention and in what manner the same is to be performed, I declare that what I claim is—

40 A stomacher formed of rectangular material, the threads of which lie transversely to the length of the stomacher to render it elastic in all directions, and the ends of which are provided with a plurality of flaps *b*, securing-straps extending from said flaps and a binding around the entire margin, of said material, substantially as described.

45 In testimony whereof I affix my signature in presence of two witnesses.

WILHELM JULIUS TEUFEL.
